ELECTRICAL APPARATUS FOR TRANSMITTING SIGNALS.

1,166,034.

Specification of Letters Patent. Patented Dec. 28, 1915.

Application filed March 9, 1915. Serial No. 13,228.

To all whom it may concern:

Be it known that I, Dr. WALTHER AKEMANN, residing at Essen-on-the-Ruhr, Germany, a citizen of the German Empire, have 5 invented a certain new and useful Improvement in Electrical Apparatus for Transmitting Signals, of which the following is a specification.

This invention relates to an electrical apparatus 10 for transmitting signals, the apparatus comprising a transmitter, a receiver, provided with a reading device indicating the desired setting, and a setting device by means of which the desired setting, observed 15 on the receiver, will be accomplished on the part to be adjusted, this setting being independent of the receiver.

Signal transmitting apparatus are known 20 wherein the receiver is provided with a pointer, which, upon the setting of the transmitter, makes a corresponding deflection and returns to a fixed mark by the use of the setting device. Such signal transmitting apparatus provides a very convenient 25 use of the setting device, as the reading is always done at the same place, and the operator never needs to note down the numbers, but these apparatus possess the disadvantage, that in all the receivers, the motor 30 must be mounted on a movable part of the setting device, or, if placed on a stationary part, must be provided with a special revolving-gearing or the like.

The object of the present invention is now 35 to provide an electrical apparatus for transmitting signals of the kind referred to above, in which the service of the setting device is equally practicable as in the above-named apparatus, but which, however, is devoid 40 of the enumerated disadvantages in said known apparatus.

In the accompanying drawing, one embodiment of this invention is illustrated and Figure 1 shows a diagrammatic horizontal 45 section of the electrically driven apparatus for transmitting signals, and Fig. 2, a diagrammatic top plan view of the same.

In the stationary transmitter housing A are revolvably mounted two armatures B 50 and C, one of which, B, serves to transmit a preliminary setting, and the other, C, to transmit the fine adjustment. Both armatures are provided with a common setting shaft D which is revolvably by means of a hand wheel d¹ which has driving connection 55

with the armature B through a worm gear 60 ing d² b¹, and with the armature C by means of beveled gears d³ E, and a pair of spur gears E¹ c¹. The two armatures B and C are each mounted on the shaft b² and c² respectively which projects through the cover a¹ of the transmitter housing. At its free end the shaft b² carries a graduated disk B³ provided with a scale b⁴ and the shaft c² carries a graduated disk C³ having a scale 65 c⁴. To read the scale b⁴ a fixed mark a² is provided on the cover A¹ and for reading the scale c⁴ a similarly arranged fixed mark a³ on the cover A¹.

In the fixed receiver housing F are rev- 70 olably mounted two armatures G and H. The armature G for the primary setting is in a well known manner connected with the transmitter armature B through a three-phase conductor J and the armature H for 75 the fine-setting system is connected with the transmitter armature C through a three-phase conductor K. The two armatures G and H are respectively mounted on the shafts g¹ and h¹ which project through the 80 cover F¹ of the receiver housing F. The shaft g¹ carries at its free end a graduated disk G² provided with a scale g³, and the shaft h¹ carries a graduated disk H² pro- 85 vided with a scale h³. For reading the scale g³ a fixed mark f² is provided on the cover F¹ of the housing F and for reading the scale h³ a mark f³ is similarly arranged on the cover F¹.

In the receiver housing F is moreover 90 mounted the driving shaft M provided with a hand wheel m¹, and by means of which the desired setting may be accomplished of the part to be set, for instance, the sight carrier of a gun sighting device, this setting 95 having been previously observed on the graduated disks G² and H² of the receiver. This setting device has a reading device with a graduated disk N for the preliminary 100 setting and a graduated disk P for the fine setting. The graduated disk N provided with the scale n¹ is mounted on the free end of the shaft N² projecting through the cover F¹, which shaft is mounted in such a manner in the housing F that the graduated disk N lies directly at the side of the graduated disk G². The graduated disk P mounted on the shaft P² and provided with a scale p¹ is now arranged in an exactly similar manner 105 relative to the graduated disk H². The fixed 110

mark f^4 on the cover F^1 belongs to the scale n^1 and a fixed mark f^5 belonging to the scale p^1 is similarly situated on the cover F^1 . The two marks f^2 and f^4 are situated on the part 5 of the cover F^1 which lies between the graduated disk G^2 and N and are connected to represent a double headed arrow. In exactly the same manner are the marks f^3 and f^6 arranged.

- 10 The graduated disk N is in driving connection with the driving shaft M through the worm gearing $m^2 n^3$ and the graduated disk P through the spur gears $m^3 Q Q^1 p^3$. The worm gearing $m^2 n^3$ and $d^2 b^1$ possess 15 the same ratio of transmission as does also the spur gears $m^3 Q Q^1 p^3$ and $d^3 E E^1 c^1$. Furthermore the graduated disks N and G^2 on the one hand, and the graduated disks P and H^2 on the other hand, possess the same 20 divisions and enumerations which is made possible by the above-named selection of the transmission ratio.

The use and operation of the described 25 device need no further explanation.

It is also obvious that this device possesses

considerable advantages over the ones described in the beginning of the specification.

I claim:—

In electrical apparatus for transmitting signals, a receiver with a reading device for 30 indicating the desired setting and a setting device for setting the member to be adjusted to the setting observed on the receiver, but independently of said receiver; said reading device comprising an armature and a movable graduated disk in driving connection therewith; said setting device comprising a movable graduated disk arranged adjacent to said first graduated disk, both of said disks being provided with identical graduation and numeration; said second graduated disk having driving connection with said member.

The foregoing specification signed at Bar- 35 men, Germany, this second day of February, 40 1915.

WALTHER AKEMANN. [L.S.]
In presence of—

HELEN NUFER,
ALBERT NUFER.
